HAND-GRIP WEIGHT FOR EXERCISING OR THE LIKE

Eugene G. Sutcliffe, Kirkwood, Mo.
(122 E. Main Ave., St. Louis, Mo.)

Filed Sept. 23, 1963, Ser. No. 76,695

Term of patent 14 years

(Cl. D34—5)

FIG. 1

FIG. 2

FIG. 3

FIG. 4

FIG. 1 is a top view of a hand-grip weight for exercising or the like showing my new design.

FIG. 2 is a side elevation thereof, the opposite side being substantially similar in appearance.

FIG. 3 is a bottom view thereof; and

FIG. 4 is an end view thereof, the opposite end being substantially similar in appearance.

I claim:

The ornamental design for a hand-grip weight for exercising or the like, substantially as shown and described.
